(57) **CLAIM**

We claim the ornamental design for a pliers grip, as shown and described.

DESCRIPTION

FIG. 1 is a first perspective view of an embodiment of a pliers grip embodying our design;

FIG. 2 is a second perspective view of the pliers grip of FIG. 1;

FIG. 3 is a third perspective view of the pliers grip of FIG. 1;

FIG. 4 is a top view of the pliers grip of FIG. 1;

FIG. 5 is side view of the pliers grip of FIG. 1;

FIG. 6 is bottom view of the pliers grip of FIG. 1;

FIG. 7 is first end view of the pliers grip of FIG. 1; and,

FIG. 8 is a second end view of the pliers grip of FIG. 1.

The scale shown in the drawings is for illustrative purposes only and forms no part of the claimed design.
